UNITED STATES PATENT OFFICE.

JAMES F. EVANS, OF PORTLAND, MAINE, ASSIGNOR OF ONE-HALF TO
WALTER FICKETT, OF STROUDWATER, MAINE.

DESIGN FOR A BILLIARD-BRIDGE.

SPECIFICATION forming part of Design No. 29,997, dated January 10, 1899.

Application filed December 9, 1898. Serial No. 698,782. Term of patent 3½ years.

To all whom it may concern:

Be it known that I, JAMES F. EVANS, a citizen of the United States of America, and a resident of Portland, Cumberland county, 5 State of Maine, have invented a certain new and original Design for a Billiard-Bridge, of which the following is a specification.

My invention relates to a design for billiard-bridges such as are used for cue-rests in the 10 game of billiards.

The design consists of the peculiar ornamental conformation of the billiard-bridge shown in the accompanying drawings, in which—

15 Figure 1 is a front elevation, and Fig. 2 is an end elevation.

The bridge A is composed of a skeleton outline having a vertical bar c, connecting the top and bottom of the bridge. The base or 20 bottom e is in the form of a flat arch, and the ends f are formed with an inward-projecting curve of comparatively large radius.

The top of the bridge has the general form of a flat arch parallel with the base, there be-

ing three corrugations or recesses a b b. The 25 recess a is directly over the central bar c, while the recesses b b are at equal distance on each side. The corners where the sides join the top and bottom are curved or rounded off. d represents the socket for the reception 30 of the handle, and it projects outward from the central bar c, which is thickened or enlarged at the point where the socket projects.

A billiard-bridge having the above-described conformation is graceful and attractive in appearance and is a great improvement over the clumsy wooden bridge hitherto in common use, and its attractive appearance makes it readily salable. 35

I claim—

40 The design for a billiard-bridge substantially as herein described and shown.

Signed by me, at Portland, Maine, this 23d day of November, 1898.

JAMES F. EVANS.
